UNITED STATES PATENT OFFICE.

THOMAS E. ALTER, OF MOUNT PLEASANT, IOWA.

STIRRUP.

No. 909,735.

Specification of Letters Patent. Patented Jan. 12, 1909.

Application filed August 1, 1908. Serial No. 446,448.

To all whom it may concern:

Be it known that I, THOMAS E. ALTER, a citizen of the United States of America, and resident of Mount Pleasant, county of Henry, 5 State of Iowa, have invented certain new and useful Improvements in Stirrups, of which the following is a full and clear specification, reference being had to the accompanying drawing, in which—

10 Figure 1 is a perspective view of a stirrup constructed in accordance with my invention; Fig. 2 is a vertical sectional view of the same; Fig. 3 is a detail perspective view of the hanger.

15 The object of this invention is to provide a simple device whereby the stirrup will become automatically detached from the stirrup-strap should the rider be thrown and he thereby be put in danger of being dragged 20 along the ground, as more fully hereinafter set forth.

25 The hanger consists of a loop *a* for attachment to the stirrup-strap and a depending shank *b* provided at its lower end with a cross bar *c*. This cross-bar forms a swivel connection between the hanger and the stirrup, and it lies in a transverse groove in the block or bar *d* connecting the upper arms of the stirrup. The cross-bar is confined in said 30 groove by a plate *e* pivoted to the upper edge of a plate *f* fastened to the front face of the cross-bar *d*. The plate *e* is bifurcated so as to straddle the shank of the hanger and these bifurcated portions extend beyond the 35 opposite edges of the spacing block *d* and are held down on the top face of the block by

means of a latch *g* pivoted at *h* at a point below the block and having a tail-piece *i* extending forwardly and downwardly through the stirrup. This latch is held in engagement by means of a spring *j* which is clamped to the under side of the spacing block by means of a plate *k* fastened to the under side of the block and formed integral with the vertical plate *f*. 40

45 It will be observed that if the rider be thrown from the horse the foot of the rider will press the tail-piece *i* upwardly and thus unlatch plate *e*, and when plate *e* is thus unlatched the stirrup is free to fall away from the hanger, as is obvious.

50 Having thus fully described my invention, what I claim as new and desire to secure by Letters Patent, is:—

55 A stirrup having a spacing block connecting its upper ends, said block having a transverse groove in its upper face, a hanger having a cross-bar at its lower end resting in said transverse groove, a hinged plate extending across the groove and locking the 60 hanger therein, a latch pivoted to the stirrup and engaging the free end of the lock plate and having a tail-piece extending through the stirrup toward the outer side, for the purpose set forth. 65

In testimony whereof I hereunto affix my signature in the presence of two witnesses this 30th day of July 1908.

THOMAS E. ALTER.
